UNITED STATES PATENT OFFICE.

ADAM GRIESEMER, OF PUEBLO, COLORADO.

RAIL-FASTENER.

1,121,352.

Specification of Letters Patent. Patented Dec. 15, 1914.

Application filed May 11, 1912. Serial No. 696,781.

To all whom it may concern:

Be it known that I, ADAM GRIESEMER, a citizen of the United States, residing at Pueblo, in the county of Pueblo and State 5 of Colorado, have invented certain new and useful Improvements in Rail-Fasteners; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in rail-fasteners and it proposes a combination of rail fastening elements which may be embodied either in a rail joint or in a rail chair.

20 The objects of the invention are to provide a rail fastener by means of which the rails are securely held to the tie and against spreading or side play; the stresses and vibrations developed are effectually resisted 25 throughout the extent of the fastener; the rail is effectually braced and reinforced; and the drainage of moisture is effectually provided for.

20 The invention is illustrated in the accompanying drawings wherein:—

Figure 1 is a side elevation showing the features of improvement carried out in connection with a rail-joint; Fig. 2 is a cross-sectional view of the improved joint; Fig. 3 35 is a perspective view of a base plate which takes the weight of the rail and is used substantially without change both for joints and for chairs; Fig. 4 is a side elevation showing the features of improvement carried out in connection with a rail brace; Fig. 5 is a cross-sectional view of the brace shown in Fig. 4; Fig. 6 is a similar view 40 of an inside brace; Fig. 7 is a bottom plan view of the base plate, and Fig. 8 is a longitudinal sectional view on the line 8—8 of Fig. 7.

Similar characters of reference designate corresponding parts throughout the several views.

50 The rail joint shown in Figs. 1 and 2 includes the splice bars 1 which are arranged at opposite sides of the rail A and which are fashioned to overlie the web and the flanges of said rail, the outer portions of 55 said splice bars being flush with the bottom of said flanges. The weight of the rail is

sustained by a base plate 3 which is of substantially greater width than the combined width of the base of the rail and the portions of the splice bars adjoining said base. 60 The plate 3 not only sustains the weight of the rail but it serves as a reinforcement therefor and for this purpose is provided at its sides with raised longitudinal cheeks 4 against which the splice bars engage. All 65 the elements of the joint are preferably positively connected. Accordingly the splice bars are bound to one another by bolt fastenings 5 which pass through the web of the rail and they are bound to the base plate 70 by bolt fastenings 6. The base plate 3 is formed on its under side with longitudinal projections 7 (Figs. 7 and 8) which are preferably arranged in transverse rows, and under the weight of the load, sink into the 75 tie and prevent any longitudinal or side slipping of the joint. The projections 7 adjacent the bolt fastenings 6 engage in longitudinal grooves of the bolt heads 6^a of said fastenings and thus prevent the bolts from 80 turning as clearly shown in Fig. 2. The lock nuts 6^b which complete the fastenings 6 are preferably engaged upon bevel washers 6^c which not only provide a level and uniform 85 seat for said nuts but prevent any play or vibrations of the elements of the fastenings 6.

To secure the joint to the ties, spikes 8 are employed, the shanks of these spikes passing through the cheeks 4 and their heads 90 engaging partly on said cheeks and partly on the adjacent rail flanges. The bolt fastenings 6 of which any desired number may be employed (although one at each side of the rail is usually sufficient) are arranged 95 between the ties to eliminate the necessity of cutting away the latter for the reception of the bolt heads 6^a.

The plate 3 is formed in its upper side with continuous longitudinal grooves 9 100 which are preferably arranged coincidently with the longitudinal projections 7 on the under side of said plate to simplify the rolling of the latter and which serve to collect and provide for the drainage or evaporation 105 of any moisture that may accumulate under the base of the rail. It follows that the parts of the joint are prevented from rusting to any substantial extent. The projections 7 also facilitate the drainage or evaporation 110 of any moisture that may accumulate under the plate 3 since they serve to some-

what space said plate from the tie and define between said plate and the tie a multiplicity of communicating canals or channels along which water may flow or collect. It 5 is thus apparent that the construction of the plate 3 not only provides for the security of the joint and of the rail but it also aids materially in maintaining the good condition of the rail, the joint, and the tie.

10 Figs. 4, 5, and 6 illustrate the invention in its application to a rail brace. The plate 3 is an essential element of the chair and in its application to this use does not differ from its application to use in a rail joint.

15 One of the cheeks 4 of the said plate is, however, positioned immediately against the base of the rail while the other cheek 4 is positioned against the flange of a rail brace 10 of suitable form. The plate 3 is spiked 20 to the tie and is connected to the brace 10 by bolt fastenings 11 which are of the same construction as the bolt fastenings 6 already described. The fastenings 11 are arranged at the ends of the brace and adjacent the 25 sides of the tie. The spikes 12 which connect the brace to the tie are arranged to pass through the plate 3 adjacent the brace 10 and also through the base or flange of said brace and the underlying portion of 30 the plate 3. The plate 3 serves the same advantages in connection with the brace that it does in connection with the joint. The brace shown in Figs. 4 and 5 is an "outside" brace while the brace shown in Fig. 6 is an 35 "inside" brace, differing however, only in the form of the brace 10.

A rail fastening in accordance with the invention may be economically produced and readily and quickly applied, its application, whether in the form of a joint or a brace involving no interruption of traffic. Once applied, it is not liable to derangement even under conditions of heavy and frequent loads; and it consequently has a 45 relatively long efficient life, and, as already pointed out promotes the good condition of the rail and of the tie. It will be noted that the bolt fastenings associate the rail, the splice bars or the brace and the base plate in 50 a unitary manner and that the subsequent

spiking of the joint or brace to the tie will not disturb the center or engaging relation of these elements. Consequently it is unnecessary to provide for any special interfitting relation of these elements such as 55 would involve a departure from standard construction. The bolt fastenings moreover provide for the plate to be drawn with strong contact against the base of the rail and the splice bars or the brace and consequently the accumulation of moisture at any places other than in the grooves 9 is practically prevented.

Having fully described my invention I 65 claim:

1. A rail fastener including a plate upon which the rail is imposed and which is formed on its under face with projections to sink into the tie and at its sides with raised longitudinal cheeks, a reinforcing 70 element at one side of the rail having a base or flange which is confined between one of said cheeks and the flange of the rail, and bolt fastenings for the connection of said plate and said reinforcing element and including bolt heads arranged under the plate and having grooves in which adjacent projections of the plate engage.

2. A rail fastener including a plate upon which the rail is imposed and which is 80 formed in its under face with projections to sink into the tie and at its sides with raised longitudinal cheeks, a reinforcing element at one side of the rail having a base or flange which is confined between one of said 85 cheeks and the flange of the rail and bolt fastenings for the connection of said plate and said reinforcing element and including a bevel washer arranged on the flange of said element, lock nuts seating against the 90 washer, and bolt heads arranged under the plate and having grooves in which adjacent projections of the plate engage.

In testimony whereof I affix my signature in presence of two witnesses.

ADAM GRIESEMER.
